UNITED STATES PATENT OFFICE.

RICHARD H. OSGOOD AND JAMES C. BLAIR, OF COLUMBUS, OHIO, ASSIGNEES OF ONE-THIRD TO JOSEPH GIBBARD, OF SAME PLACE.

ADJUSTABLE BAIL FOR EARTHEN CROCKS.

SPECIFICATION forming part of Letters Patent No. 236,352, dated January 4, 1881.

Application filed November 13, 1880. (Model.)

To all whom it may concern:

Be it known that we, R. H. OSGOOD and JAMES C. BLAIR, of Columbus, in the county of Franklin and State of Ohio, have invented 5 a new and valuable Improvement in Adjustable Bails for Earthen Crock; and we do hereby declare that the following is a full, clear, and exact description of the construction and operation of the same, reference being had to 10 the annexed drawings, making a part of this specification, and to the letters and figures of reference marked thereon.

Figure 1 of the drawings is a perspective view of my device applied, and Fig. 2 is a perspective detail view.

This invention relates to bails or handles to be applied to crocks, pans, &c.

The invention consists in the construction hereinafter described.

20 In the drawings hereto annexed, A represents an open ring. B B represent ears, having each one end turned upon itself, forming a tube, a. Near the other end of said ears, and at the same side with tube a, is a lug, b, 25 projecting outward and downward, forming a catch. The ends b' of ears B B have perforations c. Fig. 2 shows another form of these ears B, in which the catch or lug b is punched out from the body of the ear and then formed

as above described, leaving a slot, d. C represents a handle having hooked ends e e.

In use the ring A is to be slipped through tubes a a, so as to bring the ears upon opposite sides thereof. The handle is hooked into the ends of perforated ears B B, and the ring 35 A is sprung around the crock, pan, or other article needing a handle. The catches b are then made to gripe the edge of the article held, or a shoulder thereon, and the whole will be secure.

40 In case of breakage the bail can be readily applied to another article.

The various parts of this device can be made of any suitable material.

What we claim is—

45 As an improvement in bails for earthenware vessels, an ear having a tube, a, and a catch, b, cut out of the body of the ear, substantially as set forth.

In testimony that we claim the above we have 50 hereunto subscribed our names in the presence of two witnesses.

RICHARD H. OSGOOD.
JAMES C. BLAIR.
